(57) **CLAIM**

The ornamental design for a warning light assembly, as shown and described herein.

DESCRIPTION

FIG. 1 is a front perspective view of the claimed design; FIG. 2 is a rear perspective view of the claimed design;

FIG. 3 is a rear view of the claimed design;

FIG. 4 is a front view of the claimed design;

FIG. 5 is a side view of the claimed design;

FIG. 6 is a top view of the claimed design;

FIG. 7 is a bottom view of the claimed design;

FIG. 8 is a front perspective view of the claimed design wherein one possible LED orientation is visible through a front lens;

FIG. 9 is a front perspective view of the claimed design wherein one possible LED orientation is visible through a front lens; and,

FIG. 10 is a front perspective view of the claimed design wherein one possible LED orientation is visible through a front lens.

The broken line showing of internal lighting elements include a plurality of LED lights for the warning light assembly that produce illumination through the apparatus cover.
